CLAIM

The ornamental design for a trophy having a vertical time display, as shown and described.

DESCRIPTION

FIG. 1 is a front elevational view of a trophy having a vertical time display showing my new design, the broken line ornament and plaque being illustrative of environment only;

FIG. 2 is a right side elevational view thereof, the left side elevational view being generally a mirror image thereof;

FIG. 3 is a rear elevational view thereof; and

FIG. 4 is a top plan view thereof.
